UNITED STATES PATENT OFFICE.

RICHARD W. BURT, OF PEORIA, ILLINOIS.

HORIZONTAL WIND-WHEEL.

SPECIFICATION forming part of Letters Patent No. 269,511, dated December 26, 1882.

Application filed October 16, 1882. (No model.)

To all whom it may concern:

Be it known that I, RICHARD W. BURT, of Peoria, in the county of Peoria, in the State of Illinois, have invented an Improved Horizontal Wind-Wheel; and I do hereby declare that the following is a full, clear, and exact description thereof, reference being had to the annexed drawings, making a part of this specification, in which like letters of reference refer to like parts, and in which—

Figure 1 represents a sectional elevation through x' x , Fig. 2; Fig. 2 represents a sectional plan through y' y , Fig. 1.

The object of my invention is the construction of a governing device for wind-wheels of the kind in which a horizontal fan-wheel is surrounded by a wind-directing casing.

My invention consists essentially of the fan-wheel Z , having vertical axis A , gearing with a ball-governor, D , which by means of suitable levers closes more or less the screens M L of the case surrounding the fan-wheel.

In the drawings, Z Z represent the radial arms of the wind-wheel, to the extremities of which are secured the V-shaped fans Z' Z' . The vertical axis A of the wind-wheel communicates, through the gears C C' and the shaft B , a somewhat accelerated motion to the governor-shaft D . The upward pull of the collar E , when caused to rise by the too rapid rotation of the governor, gives through the lever F , pivoted at F' , a downward pull to the rods G —four in number. To the upper end of each of said rods G is pivoted a rocking brace, H , and a rod, J .

Each of the four sides of my surrounding case consists of one-third fixed screen and two-thirds (more or less) of a movable screen, M L . Said screen M L consists of top and bottom strips, M M , rigidly fixed to the vertical axis O , having bearings at top and bottom in the horizontal beams of the case. Between said two strips M M are pivoted three leaves, L L' L'' — L at the point P , and having a small chain or cord attached to its free edge to prevent its opening too far; L' pivoted to a small vertical bar, K , which not only joins both strips M M , but extends downward to the rod J , to which it is connected; and L'' pivoted

near its center at P' . Said leaf L'' is kept from turning too far by coming in contact with the small rod or wire W , secured at one end to the vertical beam U' of the case and at its other to the axis. An eye, fixed in the edge of said leaf L'' and sliding along said wire or rod W , obliges said leaf to turn when the screen M L is turned, as shown in Fig. 2, and when M L is turned flat with its side of the case the leaf L'' is caused by said wire W to coincide therewith also. The leaf L' is caused to close and is kept from opening too far by the wire or small rod W' , fixed at O and U . Said rod W' causes the leaf L also to close when the screen M L is closed. The leaves L and L' are made wider than the spaces they fill that they may not be able to swing outwardly.

In Fig. 2 the wind is coming from the upper side of the drawing, the screens being all wide open. The leaves L , L' , and L'' of the upper screen will therefore be wide open, (far as their construction permits,) and also the leaves of the right-hand screen, the leaves L'' of all the screens being opened by the wires W , and the leaves L and L' of said two screens being opened by the pressure of the wind. The leaves L and L' of the left and lower screens, M L , are, however, closed by the wind. It will now be readily seen that the wind, coming between and being directed by the leaves L L' L'' of the upper screen, impinges against the concave sides of the fans Z' and causes the wind-wheel Z to rotate in a direction opposite to the hands of a watch. The leaves of the left-hand screen gather air-current coming in contact therewith, and direct it against the concave sides of the fans Z' , thus adding to the force of rotation of the wind-wheel. The current of wind having done its work of rotating the wheel Z , escapes through the open screens at the right and lower sides of the case. Now, if the velocity of the wind increases and the wind-wheel is caused thereby to move with too great rapidity, the governor D , acting through the lever F , rods G , rocking braces H , and rods J , attached to the lower extremity of the bars K of the screens M L , closes said screens until only enough wind is let in to do no more than the work required.

I have described this wind-wheel as acted upon by the air-current coming against the upper side of said mill; but the action of the leaves and screen is practically the same, whatever the direction of the wind.

What I claim as my invention, and for which I desire Letters Patent, is as follows:

1. In enveloping cases for horizontal wind-wheels, the top and bottom strips, M M, having vertical axis O, in combination with one or more leaves, L, pivoted at P to said strips M M, and controlled by a small rod, W', fixed to the said axis O and to the frame-work of the case, and the leaf L², pivoted at P' to said strips M M, and controlled by a small rod, W, fixed to the axis O and to the frame-work of the case, substantially as set forth.

2. The horizontal strips M M, having approximately-central axis O, the horizontally-swinging leaves L, L', and L², and the rods or

wires W W', in combination with suitable frame-work and the wind-wheel Z, having V-shaped fans Z', substantially as and for the purpose specified.

3. The wheel Z, having V-shaped fans Z', 25 and the vertical axis A, a partially-enveloping case, and the horizontally-swinging approximately centrally pivoted screens M L, in combination with the bevel-gear C and C', shaft B, ball-governor D, lever F, having fulcrum 30 F', rods G, rocking braces H, and rods J, secured to said screens M L, substantially as and for the purpose specified.

In testimony that I claim the foregoing invention I have hereunto set my hand this 10th day of October, 1882. 35

RICHARD W. BURT.
